UNITED STATES PATENT OFFICE.

ALFRED WILBUR, OF ALLEGHENY, ASSIGNOR TO PHILLIPS, NIMICK & CO.,
OF PITTSBURG, PENNSYLVANIA.

FLANGING-MACHINE.

SPECIFICATION forming part of Letters Patent No. 236,285, dated January 4, 1881.

Application filed October 4, 1880. (No model.)

To all whom it may concern:

Be it known that I, ALFRED WILBUR, of Allegheny city, county of Allegheny, State of Pennsylvania, have invented or discovered 5 a new and useful Improvement in Flanging-Machines; and I do hereby declare the following to be a full, clear, concise, and exact description thereof, reference being had to the accompanying drawings, making a part of 10 this specification, in which—like letters indicating like parts—

Figure 1 is a perspective view, partly in section, of a flanging-machine illustrative of my invention. Fig. 2 is a view, in sectional elevation, of a detached portion of the shaft or spindle, the nut, and the former; and Fig. 3 is a view, in perspective, of a plate partially flanged, illustrative of the work performed by my improved machine.

20 My present invention relates to certain improvements in the flanging-machine shown and described in Letters Patent No. 157,810, granted December 15, 1874, to Richard Garstang.

25 Heretofore this machine has only been used for flanging flue-holes wholly within the sheet or plate, such as the holes a and a' , Fig. 3. This in some cases is all that is required; but there is a large class of work, as in marine 30 and other boilers of large size, where the head is made of two or more separate sheets, with flue-holes made partly in one sheet or plate and partly in another. One such sheet is shown at A , Fig. 3, and the part holes at a^2 a^3 .

35 The flanges are turned on these part holes, as at a^2 , before the different sheets are joined. Heretofore these part holes could not be flanged successfully with the machine referred to; but by means of my improvement this work can 40 be done equally as well as with holes, like a a' , lying within the sheet.

In the drawings, B represents the main frame of the machine, which may be of any suitable form and construction. An annular bed or table, C , is secured on the sleeper B' , on which the plate to be flanged is clamped or secured in any convenient way.

45 A flanging head or frame, D , of conical form, carrying on its periphery two, three, or 50 more inclined rollers, d , is employed to turn

the flange, and in so doing it bends the metal upward and forces it against the inner edge or face of an annular former, E .

A shaft, F F' , extends downward from the support B^2 and operates the flanging-head D . 55 For convenience in uncoupling this shaft, it is made in two parts, F and F' , which are connected so as to transmit the motion of one part to the other by means of an angular shank or pin and socket or box, f . Rotary motion is 60 given to the shaft, and through it to the head D , by means of gearing H H' and driving-shaft h .

In order that the shaft F F' and head D may have vertical as well as rotary motion, the 65 wheel H is keyed to the shaft by feather and groove h' , and the desired vertical movement is secured from the rotary movement by means of a screw-thread, c , formed on the part F' of the shaft, and a threaded nut in the hub of the 70 hand-wheel C' . The shaft F' also passes through the hub or sleeve E' , which is supported above the former E by arms or bars e , and in operation the nut C' is run down upon or against the sleeve E' , which thus serves as a rest.

To lock the nut and sleeve together in one direction of motion, ratchets e' , Fig. 2, are made on the adjacent edges of these two parts, which ratchets are so arranged that the nut may be turned in one direction on the sleeve, and thus 75 raise the head D until it bears against the under side of the plate to be flanged; but, on the other hand, when the shaft is rotated in the opposite direction the nut and sleeve will lock, the nut be held stationary, and the shaft 80 and head be raised by the rotation, so as to turn the flange. The force thus exerted to raise the shaft and head reacts through the nut C' , sleeve E' , and former E , thereby holding the former firmly upon the plate. 85

The parts of the machine thus far described are operated substantially as described in the patent above referred to.

90 My improvement consists in extending the shaft F' downward below the head D , as at F^2 , and this extension is journaled in a box, b , in the sleeper B' , so as to be free to move endwise in and out of the box and to rotate therein; but while in the box the bearing thus secured will prevent lateral movement or yield. 100

ing of the head D, such as would otherwise be caused by pressure on one side only of the head. The length of extension F² is, by preference, a little greater than the range of vertical movement of the head in the flanging operation; but when desired the shaft F F' can be uncoupled at f, and the lower part, F', with the head and former, be removed and replaced as before. The special function performed by 5 this extension F² is to hold the flanging-head to its work, or to prevent it from yielding sideways when turning a flange on a part hole, as at a², Fig. 3, and by means of it such work can be done on the machine as well as when 15 the hole is wholly within the plate. In the latter case the plate surrounds the head, and being clamped firmly to the table, it serves as a guide to hold the head in proper position; but even then the extension F² is an improvement 20 and enables the machine to do better work.

When a flange is to be turned in the edge of a plate, as at a², the plate is firmly clamped to the table in proper position; also, it may be braced against one of the sides of the frame 25 to prevent it from being forced away from the head; also, pins may be set in holes s in the table, against which the edge of the plate may bear, and thus prevent turning of the plate. Then, the exteusion F² holding the head from 30 yielding laterally, as described, the upward

and rotary movement of the head will turn a flange, as at a², whatever part of a circle it may represent.

By this improvement the machine is made capable of doing a large class of work which 35 could not be done by it before—namely, the flanging of part holes in the edges of plates. Thus the value and capacity of the machine are greatly increased.

I claim herein as my invention— 40

In a flanging-machine having a vertically and rotary moving flanging-head, D, with table C and former E, and in combination therewith, a two-part or jointed driving-stem, F F', extending above the flanging-head, as described, a stem or bearing, F², extending below the flanging-head, and guides or boxes both above and below the head for receiving such stems, substantially as described, whereby the flanging-head is prevented from yielding laterally under unequal pressure, while its freedom for rotary and vertical motion is preserved. 45

In testimony whereof I have hereunto set my hand.

ALFRED WILBUR.
